UNITED STATES PATENT OFFICE.

GEORGE L. SMITH AND ORAL C. SMITH, OF CLEVELAND, IDAHO.

CARBURETOR.

Application filed May 29, 1923. Serial No. 642,280.

This invention relates to vital improvements in carburetors and the primary object of the invention is to provide a novel carburetor having an improved means for thoroughly mixing the air and fuel charge together, and for atomizing and breaking up the fuel charge into small particles, thereby permitting the effective use of heavy fuel such as coal-oil and the like.

Another prime object of the invention is the provision of a rotatable draft operated propeller disposed in the carburetor for effectively mixing the charge prior to the entrance thereof into the intake manifold, the propeller serving as means for mixing the air and fuel together and breaking up the fuel into small particles.

Another prime object of the invention is the provision of a rotatable propeller and propeller shaft mounted in the body portion of the carburetor adapted to be rotated by the flow of the charge past the same, the propeller shaft being of a hollow construction and having outlet pipes carried thereby and connected with propeller blades, the pipes serving as means for spraying out the fuel into the mixing chamber of the carburetor.

A still further object of the invention is to provide an improved carburetor of the above character, which will be durable and efficient in use, one that will be simple and easy to manufacture and one which can be placed upon the market at a reasonable cost.

With these and other objects in view, the invention consists in the novel construction, arrangement and formation of parts as will be hereinafter more specifically described, claimed and illustrated in the accompanying drawings, in which drawings:

Figure 1 is a vertical longitudinal section through the improved carburetor.

Figure 2 shows perspective views of certain parts of the improved carburetor.

Figure 3 is a horizontal section through the carburetor taken on the line 3-3 of Figure 1.

Figure 4 is a horizontal section through the carburetor taken on the line 4-4 of Figure 1.

Figure 5 is a horizontal section taken through the float chamber of the improved carburetor on the line 5-5 of Figure 1.

Figure 6 is a detail horizontal section of the fuel inlet entrance of the carburetor taken on the line 6-6 of Figure 1.

Figure 7 is a detail longitudinal section through one of the blades of the propeller.

Referring to the drawings in detail, wherein similar reference characters designate corresponding parts throughout the several views, the letter A generally indicates the improved carburetor, which includes the fuel bowl 10 having its lower end provided with a plug 11 to permit the draining of the carburetor when necessary or desirable. The upper end of the bowl 10 is provided with an outwardly extending annular attaching flange 12, to which is adapted to be connected by means of bolts 13 the cylindrical mixing chamber 14. As shown the lower end of the mixing chamber 14 is also provided with an annular attaching flange 15.

A perforated mixing plate 16 is disposed between the bowl 10 and the mixing chamber 14, in order to prevent the splashing up of the fuel in the bowl into said chamber. This plate 16 is preferably clamped between the flanges 12 and 15 and is provided with a plurality of openings 17 through which excess fuel is adapted to flow back into the bowl 10. The axial center of the plate 16 supports a bearing 18, for a purpose, which will be hereinafter more fully described. As shown the extreme upper end of the cylindrical mixing chamber 14 is provided with a reduced neck 19 in which is fitted the usual type of throttle butterfly valve 20 for controlling the flow of the charge into the intake manifold. The extreme upper end of the reduced neck 19 carries an attaching flange 21 to permit the connection thereof to the said intake manifold.

Communicating with one side of the fuel bowl 10 is a valve chamber 25 provided with a suitable valve seat 26. An inlet nipple 27 extends below the valve seat and is adapted to receive the usual fuel inlet pipe or tube leading from the source of the fuel supply.

A float 30 is disposed within the fuel bowl 10 for controlling the flow of fuel into the bowl and the float is connected through the medium of an arm 31 with a needle valve 32, which is adapted to fit upon the valve seat 26. As clearly shown in Figure 1 of the

drawings the arm 31 is pivotally mounted at a point intermediate its ends upon a suitable bracket 33.

The valve chamber 25 is provided with a removable plug 28, which is disposed directly above the valve seat, which permits the cleaning of the valve and seat when necessary or desirable.

The mixing chamber 14 adjacent to its upper end supports a spider 35, the axial center of which is provided with a suitable type of thrust bearing 36.

A rotatable hollow propeller shaft 37 is rotatably mounted within the bearing 18 and the thrust bearing 15 and has its lower end disposed within the fuel chamber 10. The propeller shaft 37 at a point intermediate its ends is provided with a propeller 38 embodying a plurality of radiating blades 39.

Now it is obvious that when the charge is sucked into the intake manifold, and the same flowing past the blades of the propeller will impinge against the same and thus cause the rotation thereof, which will act as means for mixing the fuel and air together and for breaking up the fuel into small particles. The hub and blades of the propeller also support relatively small radiating tubes 40 which communicate with the bore of the hollow propeller shaft 37. During the rotation of the propeller and shaft, the fuel is sucked up through the shaft and tubes 40 and sprayed out into the mixing chamber, where the same mixes with the air.

The chamber 14 can have the outer wall thereof provided with a plurality of air inlet openings 41, which are preferably covered with suitable fabricated plates 42, which act as screens for preventing any foreign matter from entering into the mixing chamber.

It is also preferred to mount a screen 43 in the inlet nipple 27 directly below the valve seat 26, so as to prevent the entrance of any foreign matter into the fuel bowl with the fuel.

From the foregoing description, it can be seen that we have provided a carburetor of exceptionally simple and durable construc-

tion, in which means is provided for breaking up the fuel into small particles and for insuring the thorough mixing thereof with the air.

Changes in details may be made without departing from the spirit or the scope of this invention.

What we claim as new is:

1. A carburetor comprising a fuel bowl, means for controlling the level of liquid in said bowl, a mixing chamber connected with the upper end of the bowl, a plate with multiple perforations disposed between the mixing chamber and bowl having an axial shaft bearing formed therein, a spider carried by the upper end of the mixing chamber, a hollow propeller shaft rotatably carried by the bearings of the plate and spider and having its lower end extending into the fuel bowl, radial blades carried by the hollow propeller shaft, hollow spraying tubes carried by the blades and communicating with the bore of the propeller shaft, and a throttle valve arranged above the propeller, the mixing chamber having screened air inlet openings formed therein below said propeller.

2. A carburetor comprising a fuel bowl, means for controlling the level of liquid in said bowl, a mixing chamber connected with the upper end of the bowl, a perforated plate disposed between the mixing chamber and bowl having an axial shaft bearing formed therein, a spider carried by the upper end of the mixing chamber, a hollow propeller shaft rotatably carried by the bearings of the plate and spider and having its lower end extended into the fuel bowl, radial blades carried by the hollow propeller shaft, hollow tubes carried by the upper faces of said blades and communicating with the bore of the propeller shaft, a throttle valve arranged above the propeller, and means for supplying air to the mixing chamber below said propeller.

In testimony whereof we affix our signatures.

GEORGE L. SMITH.
ORAL C. SMITH.
